(57) **CLAIM**

I claim, the ornamental design for a blade arm for a ceiling fan, as shown and described.

DESCRIPTION

FIG. 1 is a top plan view of a first embodiment thereof facing in a first direction;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a perspective view thereof;

FIG. 8 is a top plan view of the embodiment of FIG. 1 facing in an opposite direction, with the corresponding views being mirror images to those of FIGS. 2-7;

FIG. 9 is a top plan view of a second embodiment of my design facing in a first direction;

FIG. 10 is a bottom plan view thereof;

FIG. 11 is a left side elevational view thereof;

FIG. 12 is a right side elevational view thereof;

FIG. 13 is a front elevational view thereof;

FIG. 14 is a rear elevational view;

FIG. 15 is a perspective view thereof; and,

FIG. 16 is a top plan view of the embodiment of FIG. 9 facing in an opposite direction, with the corresponding views being mirror images to those of FIGS. 10-15;
